ENRIQUE VILLARREAL, OF NEW YORK, N. Y.

KNIFE-WIPPING ATTACHMENT FOR TYPE-CASTING MACHINES.

1,420,595.

Specification of Letters Patent. Patented June 20, 1922.

Application filed April 9, 1921. Serial No. 459,912.

To all whom it may concern:

Be it known that I, ENRIQUE VILLARREAL, a citizen of Mexico, residing at New York, in the county of New York and State of New York, have invented new and useful Improvements in Knife-Wiping Attachments for Type-Casting Machines, of which the following is a specification.

The invention relates to wiper attachments.

More particularly the invention relates to attachments especially designed for use on a linotype machine for wiping the slug trimming knife of the machine.

Some of the objects of the present invention are: to simplify devices of the character mentioned by reducing the number of parts; to produce a more thoroughly efficient device; to make the operation of a linotype machine safe for the operator by arranging the device between the vise and the mold disk of the casting mechanism of the machine; to make provision for increasing the wiping operations of the device during one complete cycle of the operations of the machine to which it is attached. With these and other objects in view the invention resides in the particular provision, relative disposition and operation of the parts hereinafter more fully described and illustrated in the accompanying drawing, in which:

Figure 1 is an elevation of the device of the present invention, showing the slug trimming knife and the mold disk in their relative positions to the device.

Figure 2 is a sectional view taken on the line 2—2, Figure 1.

Figure 3 is a detail sectional view taken on the line 3—3, Figure 1.

Figure 4 is a perspective view of the knife wiper bar.

The device of the present invention is applicable to the Mergenthaler machine and is supported for operation on the vise forming a part of the casting mechanism, and is arranged between the said vise and the mold disk. The knife 10 for trimming the slugs after they are ejected from the mold boxes of the disk 11, forms a part of the said vise. The device comprises a bar 12 which is arranged for movement with respect to the knife 10. The bar 12 is supported for movement by the mold banking block 13 and the lower end thereof is confined in a guide opening in a part of the vise bracket

or frame. The upper end of the bar 12 has attached thereto the wiper 14. Near the upper end of the bar the same is provided with an elongated slot 15. A pin 16 extends transversely through the slot 15, and the ends of the pin 16 are supported by parts of the block 13. The pin 16 permits the up and down movement of the bar 12 and prevents the displacement of the same. Some distance above the lower extremity of the bar 12 there is arranged a stop block 17 which limits the downward movement of the bar 12. The wiper 14 is disposed to contact and traverse the trimming edges of the knife 10 in the reciprocation of the bar 12 to which it is attached. The bar 12 is moved upwardly positively and it moves downwardly under its own weight by gravity.

The upward movement of the bar 12 is effected by the employment of a lever 18 which is pivoted as at 19 to a part of the vise frame. One end of the lever 18 has connection with the bar 12—the lever is slotted as at 20 and a pin 21 carried by the bar 12 extends in the said slot. The opposite end of the lever 18 carries a pin 22 which is under the influence of a spring 23. In the normal position of the lever 18, the pin 22 lies in the path of movement of the element 24 secured to the face of the mold disk 11. The mold disk has an intermittent movement. The disk rotates and moves toward and from the vise frame. The disk 11 moves away from the vise frame for the rotation operation, and the disk moves toward the vise frame for the slug casing and ejecting operation. Because of the necessity that the disk 11 move toward and from the vise frame, the pin 22 is arranged on the lever 18 to have reciprocatory movement. When the disk 11 moves toward the vise frame, the pin 22 moves against the action of its related spring 23, and when the disk 11 moves away from the vise frame, the spring 23 moves the pin 22 back to its normal position in which it is disposed to be engaged by the element 24 on the mold disk 11. In the rotation of the disk 11, at a predetermined time, the element 24 engages the pin 22 and moves the end of the lever 18 carrying the pin 22, downwardly, and the opposite end of the lever upwardly, causing the bar 12 and its wiper 14 to move upwardly. At the end of the upward movement of bar 12, pin 22 moves out of contact

with element 24. In the upward movement of the wiper 14, the same, in contact with the trimming edges of the knife 10, wipes the same clean of all adhering particles or trimmings. It should at once be obvious that by embodying more than one element 24 the wiper 14 may be caused to wipe the trimming edges of the knife 10 more frequently. It is within the present 10 invention to employ any number of elements 24.

From the foregoing it should be manifest that, a simple and more efficiently serviceable device has been disclosed; that under 15 its relative arrangement, the element of danger to the operator is entirely eliminated.

What is claimed is:

1. A device as characterized including a 20 movable bar, a wiper carried by the bar, means for moving the bar upwardly, guiding means for causing the rectilinear movement of said bar, the said bar being free to gravitate downwardly to a normal position.
2. A device as characterized including a 25 movable bar, a wiper carried by the bar, means for moving the bar upwardly, guiding means for causing the rectilinear movement of said bar, the said bar being free to 30 gravitate downwardly to a normal position, and means for limiting the downward movement of the bar.
3. A device as characterized including a 35 movable bar, a wiper carried by the bar, and means for moving the bar upwardly, the said bar being free to gravitate downwardly to a normal position, said means including a pivoted lever, a pin carried by the lever, and a movable element which travels in a 40 path in which the said pin lies normally.
4. A device as characterized including a 45 movable bar, a wiper at the upper end of the bar, and means for moving the bar upwardly, the said bar being free to gravitate downwardly to a normal position, said

means including a pivoted lever loosely connected to said bar, a pin carried by the lever, and a movable element which travels in a path in which the said pin lies normally.

5. In a type casting machine including a 50 vise frame and a mold disk having compound movement, a slug trimming knife on said frame, a movable bar, a wiper carried by the bar and disposed to traverse the trimming edges of the said knife in contacting relation therewith, means for moving the 55 bar upwardly, the said bar being free to gravitate downwardly, said means including a pivoted lever loosely connected to the bar, a spring pressed pin carried by said lever, and an element carried by said disk which travels in a path in which the said pin lies normally in the rotation of said disk; and means for limiting the downward movement of said bar.

6. In a type casting machine including a 60 vise frame and a mold disk having compound movement, a slug trimming knife on said frame, a movable bar between the said frame and the said disk, a wiper carried by the bar and disposed to traverse the trimming edges of the said knife in contacting relation therewith, means for moving the bar upwardly, the said bar being free to 65 gravitate downwardly, said means including a pivoted lever loosely connected to the bar and arranged between the frame and mold disk and supported by the frame, a spring pressed pin carried by said lever, and an element carried by said disk which travels in a path in which the said pin lies when the lever is in a normal position, the said element 70 engaging said pin in the rotation of said disk to actuate said lever; and means for 75 limiting the downward movement of said bar.

In testimony whereof I hereby affix my signature.

ENRIQUE VILLARREAL.
